UNITED STATES PATENT OFFICE.

ADRIAN D. ADRIANCE, OF BROOKLYN, NEW YORK.

DESIGN FOR A TOY BOW.

59,317.

Specification for Design.

Patented Oct. 11, 1921.

Application filed April 30, 1921. Serial No. 459,162. Term of patent 7 years.

To all whom it may concern:

Be it known that I, ADRIAN D. ADRIANCE, a citizen of the United States, and a resident of New York, in the county of Queens and State of New York, have invented a new, original, and ornamental Design for a Toy Bow, of which the following is a specification, reference being had to the accompanying drawing, forming part thereof.

This invention, covers a toy spring bow for projecting arrows, and consists of a spring, and a tension string fastened to each end of said spring, tautly.

The object of this invention is to provide a bow of fewest parts, and a novel means of decorating same.

The accompanying drawing forms part of this specification.

Figure 1, is a plan view of a toy bow showing my new design.

Fig. 2, is a side elevation thereof.

I claim—

The ornamental design for a toy bow as shown.

Signed at Brooklyn borough, New York city, in the county of Queens and State of New York, this 25th day of March A. D. 1921.

ADRIAN D. ADRIANCE.
